Primary Examiner — Karen E Eldridge Powers

(57) **CLAIM**

The ornamental design for a long-bristled brush, as shown and described.

DESCRIPTION

FIG. 1 is a front-top-left perspective view of a long-bristled brush showing my new design;

FIG. 2 is a front-top-right perspective view of a long-bristled brush showing my new design;

FIG. 3 is a front-plan view thereof;

FIG. 4 is a back-plan view thereof;

FIG. 5 is a left elevation view thereof;

FIG. 6 is a right elevation view thereof;

FIG. 7 is a top plan view thereof; and,

FIG. 8 is a bottom plan view thereof.

The broken line showing the bristles in FIGS. 1-8 are included for the purpose of showing environmental structure and form no part of the claimed design.

1 Claim, 8 Drawing Sheets(56)
